CLAIM

The ornamental design for a flare tee holding socket, as shown and described.

DESCRIPTION

FIG. 1 is a upper right perspective of the flare tee holding socket.

FIG. 2 is a front plan view of the design for the flare tee holding socket, the rear plan view identical.

FIG. 3 is a right side plan view of the design for the flare tee holding socket, the left side plan view identical.

FIG. 4 is a top plan view of the design for the flare tee holding socket; and,

FIG. 5 is a bottom plan view of the design for the flare tee holding socket.

The dashed lines represent the flare tee and the wrenches used with the holding socket and therefore form no part of the invention.
